ANIMATED TALKING TOY WITH
BUILT-IN RECORDERHisashi Suzuki, Tokyo, Japan, assignor to Louis Marx &
Co., Inc., New York, N.Y., a corporation of New
YorkFiled May 18, 1962, Ser. No. 195,935
5 Claims. (Cl. 46—232)

This invention relates to animated toys or figures and, more particularly, to a talking animated toy or figure provided with novel means whereby the toy or figure will repeat or reproduce, in synchronism with animation of appendages of the toy or figure, information selectively imparted thereto and which information may be erased, as desired, and new information imparted to the toy or figure for repetitive reproduction thereby.

Animated toys or figures, such as animated birds, dolls, and the like, are known to the art and, in a number of instances, such toys or figures have been provided with sound reproducing mechanisms, such as a record or the like, whereby the toy or figure may be made to "speak" while also giving the effect of animation. These prior art arrangements have generally been of two types. In one type, which is generally self-contained, a record player or the like has been mounted within the body of the toy or figure so that the toy or figure will appear to reproduce sound recorded upon a record mounted upon the record player. In this particular arrangement, it is not possible for the reproduced information or talk to be changed without disassembling the entire mechanism from the body so as to be able to change the record. In other words, the animated toy or figure constantly repeats the same sound at all times.

In another known prior art arrangement, an animated toy or figure is provided with a speaker or the like which is connected to an extraneously and remotely located microphone, as through an amplifier, so that words spoken into the microphone will appear to be spoken by the animated toy or figure.

These prior art arrangements have various disadvantages. In the first case mentioned above, the conversation to be reproduced by the toy or figure cannot be changed at will and, in any event, not without removing the sound mechanism from the body of the toy or figure. The second arrangement has the disadvantages that it is not completely self-contained and portable but must be maintained at a fixed location and connected, by wiring or the like, to an extraneous and remote microphone or the like. This is inherent even though the information or conversation instantaneously reproduced by the toy figure or animal corresponds to conversation into the remote microphone or the like.

The present invention is directed to a novel form of animated toy or other figure, such as, for example, a talking bird, which is completely self-contained and portable and which will not only reproduce conversation or other information imparted thereto but in which the information reproduced by the toy or figure may be changed at will merely by erasing previous information from a recording mechanism and imparting new information thereto. To this end, the animated toy or figure of the present invention has mounted, within its generally hollow body, a motor and gearing driving animating mechanism for moving appendages of the figure, such as the head, tail, wings, and, in the case of a toy parrot, one of the two beak members. Associated with this mechanism is a tape recorder having means to dictate, erase and reproduce, this tape recorder having an endless tape associated therewith. The toy figure is provided with an internally mounted loudspeaker and with a microphone.

2

Consequently, the operator may speak into the microphone and have the conversation thus spoken recorded on the endless tape, with erasure of prior recorded information. Thereupon, and upon conditioning of the tape recorder for reproducing the conversation or the like, the tape recorder is driven to reproduce the recorded information and simultaneously the animating mechanism is energized so that the appendages of the figure are moved in a life-like manner. During erasing of previous information and recording of new information on the endless tape, only the tape recorder is energized, by means of novel switching mechanism, and the animation mechanism remains idle.

When the invention is applied, for example, to the case of an animated bird, such as a parrot, the control mechanism is mounted in a suitable base having a perch extending therefrom upon which the bird is mounted. The whole arrangement is easily portable and is preferably self-powered, as by batteries and the like.

For an understanding of the principles of the invention, reference is made to the following description of a typical embodiment thereof as illustrated in the accompanying drawings. In the drawings:

FIG. 1 is a perspective view of an animated talking parrot embodying the invention;

FIG. 2 is a side elevational view of the animated talking parrot, the internal mechanism being shown in solid lines and the outlines of the body parts being shown in broken lines;

FIG. 3 is a front elevational view corresponding to FIG. 2; and

FIG. 4 is a schematic wiring diagram illustrating the animation mechanism and associated sound recording and reproducing mechanism, together with the novel interrelated switching means.

Referring to FIGS. 1, 2 and 3, the invention is illustrated as embodied in a toy parrot having a substantially hollow body 1, a substantially hollow head 7, a beak part 9 on the head 7, a tail 11, and wings 23. Head 7, tail 11 and wings 23 are appendages movable relative to body 1, and beak part 9 is an appendage movable relative to head 7. The animating mechanism A (FIGS. 2 and 3), is mounted within the body 1, and the sound reproducing mechanism, generally indicated at B, is mounted within a suitable base having a perch extending upwardly therefrom and supporting the parrot, as best seen in FIG. 1.

Head 7 is pivotally connected to body 1 at 17, so that it may be oscillated horizontally through an arc concentric with pivot 17. Beak part 9 is pivoted to the head 7 intermediate its ends, as indicated at 8. The tail has an operating member 11 extending thereinto, and this operating member is pivoted to body 1 as at 10. Wings 23 are likewise pivoted to the body 1, as indicated, these wings having operating members extending thereinto.

The mechanism A includes an electric motor 2 which is mounted in a frame, generally indicated at 14, also supporting reduction gearing driven by the motor 2. Through this reduction gearing, motor 2, when energized, rotates cranks 3 and 4. A link or connecting rod 5 connects the crank 3 to the inner end of the movable beak 9 so that, when crank 3 is rotated, the movable beak part 9 is oscillated. A second link or connecting rod 6 connects the crank 3 to a portion of operating member 11 spaced from the pivotal mounting 10 thereof so that, when crank 3 is rotated, the tail will be oscillated or swung from left to right by the member 11.

As best illustrated in FIG. 2, mechanism A includes a rod or wire bent into a generally T-shape including a bifurcated generally horizontal "head" portion 16 providing a slot in which is engaged the free end 12 of the crank 4. One end of this wire or rod is pivoted at 13 to

the frame 14, and the "stem" 15 of the rod extends through a radial slot 7' in the lower portion of the head 7 adjacent the pivot 17. Thus, as crank 4 is rotated, the free end portion 15 will be oscillated so that, in turn, the head 7 will be oscillated from right to left about its pivotal mounting 7 and relative to the body 1.

A cam disk 19 is fixed to the axial part of the crank 4 and has fingers 18 projecting from its periphery. A bent rocker rod 21 is pivoted at 20 to the frame 14, and has a spring 22 connected thereto, the spring 22 being also connected to the frame 14. Due to the bias exerted by the spring 22, a part 21a of the rod 21 is maintained in engagement with the cam disk 19 and with the fingers 18 of the latter.

The means for operating the wings 23 includes pivoted operating members 23a extending into the wings, and which have angularly off-set inner ends formed with co-incident slots 23b. A free end of the rod 21 is engaged in both slots 23b. Thus, as crank 4 and cam disk 19 are rotated, the operating members 23a will flap the wings 23 as the part 21a of the rod 21 rides over the fingers 18 of the cam disk 19. It will thus be noted that the mechanism A will oscillate head 7 and beak portion 9, as well as oscillating tail 11 and flapping wings 23, all in timed relation to each other, to give a lifelike animation to the figure.

For a purpose to be described, a microphone 24 is mounted within the body 1, preferably adjacent the front of the body, and a loudspeaker 25 is also mounted within body 1, preferably adjacent a side of the body. Furthermore, a pilot lamp 26 is provided at the eye location of the parrot.

Referring more specifically to FIG. 4, the sound recording and reproducing mechanism B comprises a tape recorder provided with an endless recording tape 27. The tape recorder has a recording and reproducing head 28, and the tape 27 is driven by an electric motor 29. The tape recorder further includes an erasing means 30 including a permanent magnet 31 which may be swung selectively into erasing relation with the tape 27.

As best seen in FIGS. 1 and 4, the operation of the animation mechanism as well as the sound mechanism is controlled by switches S1 and S2. The switch S1 is a type of switch which moves between open and closed positions, and vice versa, upon successive depressions of its operating button. As best seen in FIG. 4, the switch S1 is a normally open, three-arm switch. When switch S1 is closed, one arm connects a conventionally illustrated battery to the sound recording and reproducing system, a second arm partially completes an energizing circuit for the motor 2 by connecting a conventionally illustrated battery into this circuit, and the third arm connects the motor 29 across another conventionally illustrated battery, the latter two batteries having the same voltage, such as 1.5 volts.

The switch S2 is a "record-reproduce" switch which is normally biased to the "reproduce" position. When switch S2 is operated, as by pressing its operating button, it conditions the sound reproducing system to "record" and, at the same time, moves the permanent magnet 31 into operative relation with the tape 27 so as to erase sounds on the tape in advance of the position at which the tape passes the record-reproduce head 28, as indicated by the arrow. A switch S3 is operatively associated with the switch S2 for conjoint operation therewith and, when switch S2 is in the "reproduce" position, the switch S3 is closed. When switch S2 is moved to the "record" position, the switch S3 is opened so that motor 2 will remain deenergized even though the switch S1 is closed. A switch S4 is also operatively connected with the switch S2 so that, when the switch S2 is in its normal or "reproduce" position, the speaker 25 is connected in circuit with the sound amplifying system. When switch S2 is moved to the "record" position, switch S4 disconnects the speaker 25 from the remainder of the sound system, and

connects an impedance into such system, this impedance replacing the normal impedance of the speaker 25. As stated, switch S2 is of the type which is normally biased to one position, and which, after pressure thereon is released, will return to such one position.

The described arrangement operates as follows. To begin with, the switch S1 is operated and thus connects the several batteries into the circuits. Switch S2 is then pushed to the "record" position and a conversation then may be recorded on the endless tape 27 by speaking into the microphone 24. At this time, the speaker 25 is disconnected from the circuit by the switch S4, and the motor 2 for the animating mechanism remains deenergized due to the switch S3 being opened. After the desired information thus has been recorded upon the endless recording tape 27, the switch S2 is released and the system is automatically switched over to reproduce the recorded sound respectively. Thereby, the speaker 25 is reconnected into the system and the motor 2 for the animating mechanism is energized by closure of the switch S3. The tape recorder thus reproduces, through the speaker 25, the previously recorded information and, at the same time, due to energization of the motor 2, the animating mechanism is operated. Consequently, during reproduction of the recorded sound, the head 7 will be oscillated back and forth relative to the body 1, the beak 9 will move up and down, the tail 11 will be swung back and forth, and the wings 23 will be fluttered or flapped. The tail 11 swings from left to right and vice versa.

By virtue of the combined animation and the sound reproduction, the toy parrot will appear lifelike. The information reproduced by the toy parrot may be changed readily, at any time, by depressing the switch S2 which will bring erasing device 30, and particularly its permanent magnet 31, into operative relation with the endless tape 27. It will be noted that, when information is being recorded upon the endless tape 27, the motor 2 is deenergized so that there will be no animation of the appendages of the parrot during recording. This has the desirable effect that noise due to the motor, its gearing, and the movable appendages will not be recorded upon the tape so that the words spoken into the microphone 24 will be clearly recorded and reproduced.

While the present invention is primarily intended for amusement, it will be appreciated that it has value as an advertising device as any desired advertisement may be recorded readily and easily on the endless tape, and then reproduced together with animation of the bird. Due to the simplicity of construction of the invention arrangement, it has a very great practical value not only for amusement but also for advertising purposes.

While a specific embodiment of the invention has been shown and described in detail to illustrate the application of the principles of the invention, it will be understood that the invention may be embodied otherwise without departing from such principles.

What is claimed is:

1. A talking figure comprising, in combination, a hollow body; appendages movably connected to said body; motor driven animating mechanism in said body and connected to said appendages, said animating mechanism, when activated, moving said appendages relative to said body; a motor driven tape recorder having an erase head and a record-reproduce head; and endless record tape on said recorder; a microphone and a speaker within said body and connected to said recorder; and selector means operable to switch said recorder from a "reproduce" condition to an "erase-record" condition whereby erasure of previously recorded sounds takes place concurrently with the recording of new sounds; said selector means, in the "reproduce" position, connecting said speaker to said record-reproduce head and activating the motor of said animating mechanism and, in the "erase-record" position, connecting said microphone to said

record-reproduce head and deactivating the motor of said animating mechanism.

2. A talking figure, as claimed in claim 1, in which said animating mechanism and said tape recorder are driven by electric motors; said selector means comprising selector electric switch means.

3. A talking figure, as claimed in claim 2, in which said selector switch means is biased to the "reproduce" position.

4. A talking figure, as claimed in claim 2, in which said selector switch means includes switch arm means selectively operable to connect either said microphone or said speaker to said record-reproduce head, and a first switch included in the energizing circuit of the electric motor for said animating mechanism.

5. A talking figure, as claimed in claim 4, including

control switch means selectively operable to connect said animating mechanism and said tape recorder to a source of electric potential, said control switch means including a second switch connected in the energizing circuit of the motor of said animating mechanism in series with said first switch, and a third switch connected in the energizing circuit of the motor of said tape recorder.
